Fig. 1.

Fig. 4.

A technical drawing of a circular component, possibly a bearing or a hub. It features a central circular hole with a textured or serrated inner edge. Surrounding this is a ring of smaller holes. The outermost edge of the component is marked with a series of small circles. Two specific features are labeled: '67' is located at the top, pointing to a hole in the outer ring; '65' is located on the left side, pointing to a hole in the outer ring.

UNITED STATES PATENT OFFICE.

WALTER B. NYE, OF BROOKLINE, MASSACHUSETTS, ASSIGNOR, BY MESNE ASSIGNMENTS, TO THE NEW YORK FILTER MANUFACTURING COMPANY, OF NEW JERSEY.

FILTER.

SPECIFICATION forming part of Letters Patent No. 617,861, dated January 17, 1893.

Application filed January 27, 1893. Serial No. 668,224. (No model.)

To all whom it may concern:

Be it known that I, WALTER B. NYE, a citizen of the United States, residing in Brookline, in the county of Norfolk and State of Massachusetts, have invented an Improvement in Filters, of which the following description, in connection with the accompanying drawings, is a specification, like letters on the drawings representing like parts.

This invention relates to filters of that class commonly known as "mechanical" filters, in which a revolving agitator is employed to loosen up the filter-bed to facilitate the removal of foreign matter intercepted by the filter-bed.

My present invention has for its object to provide rotatable means by which the impurities may be removed from the surface of the filter-bed when the agitator is inserted into said bed and is revolving therein. The rotatable means may and preferably will be a plurality of pipes or conduits, preferably connected to the agitator to revolve therewith in close proximity to the upper surface of the filter-bed when the agitator is in substantially its lowest position in said bed, and the said rotatable conduits preferably communicate with a central well, through which the wash water is discharged. The rotatable conduits are preferably provided with enlarged inlet ports or openings, which may be and preferably are located near the outer ends of said conduits and are especially adapted to effect the removal of the impurities which are thrown by centrifugal action toward the outer edge of the filter-bed. These and other features of this invention will be pointed out in the claims at the end of this specification.

Figure 1 represents in section and elevation one form of mechanical filter embodying this invention; Fig. 2, a sectional detail on the line 2 2, Fig. 1; Fig. 3, a sectional detail on the line 3 3, Fig. 1; and Figs. 4 and 5, details to be referred to.

In the mechanical filter herein shown as embodying this invention, A represents a circular tank or vessel to contain the filter-bed, (represented by the dotted line a.) The filter-bed a rests upon a bottom composed, as shown, of a series of radial collecting trays or pans a', each having a perforated or fo-

raminous top a² and communicating with a passage a³ in a casting a⁴, forming part of a central well, the said casting having a chamber a⁵, with which communicates a pipe a⁶, 55 having a branch pipe a⁸, and the said casting has formed integral with it a pipe a⁹, extended through the chamber a⁵ and communicating at one end with a pipe a¹⁰, provided with a branch pipe a¹², and having its 60 other end communicating with a cylinder a¹³, erected upon and secured to the said casting, the said cylinder extending above the filter-bed a. The casting a⁴ is provided with a thickened flange a¹⁴, which rests upon the 65 bottom proper of the tank or vessel, which bottom may be two layers a²⁰ a²¹, of board, upon which is laid a bed a²², of cement, in which the collecting trays or pans are placed.

The vessel or tank A contains a rotatable 70 agitator, preferably of the construction herein shown, it consisting of a series of radial arms b, provided with depending teeth b' and attached to a hub b² fast on a shaft or rod b³, extended up out of the tank and, as herein 75 shown, into a cylinder b⁴, wherein it is provided with a piston b⁵. (Indicated by dotted lines.) The cylinder b⁴ is provided with substantially diametrically opposite guideways b⁶, (see Fig. 4,) which extend longitudinally 80 of the said cylinder and into which project lugs b⁷ on the piston, so that the piston may be reciprocated while the cylinder is being revolved by suitable driving mechanism, which is shown as a bevel-gear b¹⁰, fast to the cylinder, a bevel-pinion b¹², meshing therewith and fast on a counter-shaft b¹³, provided with a large gear b¹⁴, with which meshes a pinion b¹⁵ on a main shaft b¹⁶, provided with a loose pulley b¹⁷ and with a clutch mechanism b¹⁸. 85

The shafts b¹³ b¹⁶ are suitably supported in uprights b²⁰, erected upon cross-beams b²², secured to the tank A. The piston is reciprocated in its cylinder b⁴ by means of water or other fluid admitted into the opposite ends of 95 the cylinder, it being admitted directly into the upper end through an inlet-pipe b²⁴ and into the lower end by a branch pipe b²⁵. The pipes a¹⁰ a¹² are provided with suitable valves b²⁶ b²¹ and the pipes a⁷ a⁸ with suitable 100 valves b²⁸ b²⁹.

During the process of filtration the agitator

tered water is admitted into the filter-bed vessel A through the pipes a^9 a^{10} and cylinder a^{13} , the valve b^{30} being opened and the valve b^{31} being closed. The unfiltered water percolates through the filter-bed and passes into the collecting-trays a' , from which it runs through the passages a^8 into the chamber a^6 and thence through the outlet-pipe a^7 for the filtered water, the valve b^{32} being open and the valve b^{33} being closed.

When it is desired to wash the filter-bed, the agitator is lowered and the teeth b' penetrate into the filter-bed to near the perforated bottom thereof and the said agitator is revolved to stir up or loosen the sand or other granular material of which the filter-bed is composed, so that filtered water passing up through the filter-bed may cleanse the same of impurities and foreign matter intercepted by it.

The filtered water for washing the filter-bed is admitted into the tank through the branch pipe a^8 , the valve b^{32} being closed, and then passes through the pipe a^7 into the chamber a^6 , from whence it passes through the passages a^8 into the collecting-trays a' and thence up through the filter-bed, carrying with it the intercepted matter in the filter-bed. The greater portion of the wash-water, with its impurities, passes from the tank down through the cylinder a^{13} of the central well, into and through the pipes a^9 a^{10} , and out through the branch pipe a^{13} , the valve b^{31} being open and the valve b^{30} being closed.

A considerable portion of the intercepted matter carried to the surface of the filter-bed is thrown by centrifugal action, caused by the rotating agitator, toward the circumference or outer edge of the filter-bed—that is, toward the sides of the tank or vessel—and this portion of the intercepted matter may be removed by means of one or more conduits, which in the present instance are two in number and are shown as horizontally-extended pipes c , carried by the radial arms b , to which they may be secured in any suitable or desired manner. The pipes c extend to near the circumferential wall of the tank and may and preferably will be provided with enlarged inlets, preferably hollow castings c' , having enlarged mouths c^2 , which incline downward from the said pipes and which are revolved in close proximity to the upper surface of the filter-bed. Each pipe or conduit c may be provided with a depending or draft leg c^4 , extended into the cylinder a^{13} of the central well and movable vertically therein when the agitator is raised and lowered.

Instead of providing each conduit or pipe c with a depending leg all the pipes c may be connected to a single vertical leg. The depending leg of the conduit or conduits acts as a siphon to draw the water containing intercepted matter through the said conduits into the cylinder a^{13} of the central well, from which it is carried off through the pipes a^9 a^{10} and

The main body of wash-water passing directly down through the cylinder a^{13} of the central well creates a suction which facilitates the removal of the intercepted matter near the walls of the tank. The piston rod or shaft b^8 may and preferably will be guided and supported at its lower end by a guide-tube d , attached by arms d' to a ring d^2 , which may be clamped or secured to the casting a^4 by the cylinder a^{13} .

I have herein shown the conduit c as separate from the agitator-arms b ; but it is evident that the said arms may be made hollow and provided with an inlet opening or openings, so as to form conduits for the wash-water.

The agitator may be revolved in either direction, but preferably so that the mouth of the conduit c is drawn through the water rather than forced through it.

I claim—

1. In a filtering apparatus, the combination of the following instrumentalities, viz: a filter tank or vessel containing a filter-bed therein, an agitator adapted to be inserted into and withdrawn from said filter-bed, a central well extended above the filter-bed, and a conduit for the intercepted matter washed from said filter-bed, communicating with said central well and extended toward the walls of the filter-tank above the filter-bed and provided with an inlet port or opening near its end, for the purpose specified.

2. In a filtering apparatus, the combination of the following instrumentalities, viz: a filter tank or vessel containing a filter-bed therein, a central well extended above the filter-bed, and a conduit for the wash-water extended above the filter-bed toward the outer edge thereof and provided with an inlet port or opening and with a depending leg which communicates with and discharges the wash-water from said conduit into said central well, substantially as and for the purpose specified.

3. In a filtering apparatus, the combination of the following instrumentalities, viz: a filter tank or vessel containing a filter-bed therein, and a conduit for the wash-water extended from the center toward the outer edge of the filter-bed above the upper surface of the same and provided with an inlet port or opening and with a depending outlet or discharge leg, substantially as described.

4. In a filtering apparatus, the combination of the following instrumentalities, viz: a filter tank or vessel containing a filter-bed therein, a rotatable agitator adapted to be inserted into and withdrawn from said filter-bed, and a conduit for the wash-water attached to said agitator to rotate therewith above the filter-bed when the agitator is inserted into said bed, and comprising a substantially horizontal pipe extended from near the center to near the outer edge of the filter-bed and provided near its outer end with an inlet port or open-

ing and at its inner end with a depending leg, for the purpose specified.

5. In a filtering apparatus, the combination of the following instrumentalities, viz: a filter tank or vessel containing a filter-bed therein, a rotatable agitator adapted to be inserted into and withdrawn from said filter-bed, and a conduit for the wash-water attached to said agitator to rotate therewith above the filter-bed when the agitator is inserted into said bed, and comprising a substantially horizontal pipe extended from near the center to near the outer edge of the filter-bed and provided near its outer end with an inlet port or opening and at its inner end with a depending leg, and a central well with which the said depending leg communicates and in which it moves vertically, substantially as described.

6. In a filtering apparatus, the combination of the following instrumentalities, viz: a filter tank or vessel containing a filter-bed, a rotatable agitator adapted to be inserted into and withdrawn from said filter-bed, and a conduit for the wash-water in said tank comprising a pipe extended above the filter-bed from near its center toward its outer edge and provided with an inlet port or opening near its outer end into which the wash-water above the filter-bed may pass when the agitator is inserted into said filter-bed, for the purpose specified.

7. In a filtering apparatus, the combination of the following instrumentalities, viz: a filter tank or vessel containing a filter-bed, a rotatable agitator adapted to be inserted into and withdrawn from said filter-bed, and a conduit for the wash-water in said tank comprising a pipe extended above the filter-bed from near its center toward its outer edge and provided with an enlarged inlet port or opening near its outer end into which the wash-water above the filter-bed may pass when the agitator is inserted into said filter-bed, for the purpose specified.

8. In a filtering apparatus, the combination of the following instrumentalities, viz: a filter tank or vessel containing a filter-bed therein, an agitator to loosen up the filter-bed, and a conduit for the intercepted matter washed from said bed extended from the center toward the outer edge of the filter-bed above the upper surface thereof and provided with an inlet-opening near its outer end, for the purpose specified.

In testimony whereof I have signed my name to this specification in the presence of two subscribing witnesses.

WALTER B. NYE.
